UNITED STATES PATENT OFFICE.

ERNEST C. KUEHL, OF CHICAGO, ILLINOIS, ASSIGNOR OF ONE-HALF TO HERBERT C. LUST, OF CHICAGO, ILLINOIS.

NEEDLE HOLDER FOR SOUND-REPRODUCING MACHINES.

1,414,517.

Specification of Letters Patent. Patented May 2, 1922.

Application filed January 10, 1921. Serial No. 436,130.

To all whom it may concern:

Be it known that I, ERNEST C. KUEHL, residing at Chicago, in the county of Cook, State of Illinois, having invented certain new and useful Improvements in Needle Holders for Sound-Reproducing Machines, do hereby declare that the following is a full, clear, and exact description of the same.

10 My invention relates to needle-holders for sound-reproducing machines, and consists in the matters hereinafter described and then pointed out in the appended claims.

15 In the accompanying drawing, Fig. 1 is a view of the device with a needle in place and attached in position on the machine;

Fig. 2 is a view of the device with its sleeve in section and the interior parts in plan;

20 Fig. 3 is an end view of the device with the needle in section.

Fig. 4 is a longitudinal sectional view on the line 4—4 of Fig. 1 showing the parts in their positions after a needle is inserted;

25 Fig. 5 is a cross-sectional view on the line 5—5 of Fig. 4;

Fig. 6 is a detail view of the lever jaw, and

Fig. 7 is a perspective view of the device 30 with the sleeve broken away and showing the lever jaw in its position before the needle is inserted.

In the drawing, in which the several views show the parts enlarged for the purpose of clearer illustration, the reference numeral 10 indicates the metallic body of the needle-holder, and 11 a tubular metallic sleeve frictionally engaging the body and forming a permanent casing enclosing the 35 working parts. The body 10 is cylindrical in cross-section, having its outer end or head rounded and projecting slightly beyond the corresponding end of the sleeve, and its inner end or base is provided with a

40 pin 12 or any other suitable means for attaching it to the stylus-bar 13 of the sound-box 14 of the machine. The body is provided with a central or axial bore 15 providing a needle-hole and having a bell-mouth 16; in the wall of the needle-hole the body is provided with an axial groove 17 which extends the length of the bore and is V-shape in cross-section with its apex substantially flush with the outer or enlarged 45 end of the bell-mouth. Opposite the groove

17 the body is provided with a radial channel or kerf 18 leading from the bore outwardly through the perimeter of the body and extending from its rounded head to a point adjacent its base. The kerf extends 60 axially the length of the bore, and at their inner ends adjacent its base the body is provided with a cross-bore 19 which is slightly larger in diameter than the width of the kerf and forms a chamber to receive a coil-spring 20. A lever 21 is pivotally mounted in the kerf; its head or jaw 22 substantially fills the outer end of the kerf and projects slightly into the bore 15, and the end of the 65 jaw is rounded at its outer portion to correspond with the shape of the outer end of the body 10 and is beveled inwardly at its inner portion to form a cam-surface 23 in correspondence with the flare of the bell-mouth 16. The inner end of the lever is reduced or cut-away along its inner edge to form a comparatively narrow finger 24 which rests upon the outer end of the spring to compress it. The lever 21 is provided on its outer edge with a lateral pair of wings 70 25 forming a pintle bearing in seats formed by a cross-groove 26 cut at the margins of the kerf; the seats are of sufficient depth to bring the outer faces of the wings flush with the perimeter of the body, and when the 75 lever is positioned and the sleeve is slipped in place upon the body the wings 25 are held in their seats so that while the lever is free to swing upon its pintle it is thus held against displacement. The finger 24 of the 80 lever is disposed at a slight angle inwardly from the line of the outer edge of the jaw and toward the axis of the body, to allow sufficient play of the parts when the jaw moves inwardly into the bore under the 85 stress of the spring when the needle 27 is removed.

When the parts are assembled the sleeve forms a permanent casing for the parts and the tension of the spring throws the finger 100 of the lever out to its limit defined by the inner wall of the sleeve, and throws the jaw inwardly into the needle-hole. When a needle 27 is inserted in the needle-hole it engages the cam 23 on the end of the jaw 105 27 and throws the jaw slightly outward against the sleeve, which movement causes the finger of the lever to compress the spring all as shown in Fig. 4, and when the needle is in place between the bore and jaw the 110

tension of the spring causes the jaw to crowd the needle into the V-shaped groove 17, and the walls of this groove together with the inner edge of the jaw provide a 5 triangular seat for the needle as shown in Figs. 3 and 5, with the result that a round needle is held in its seat securely against vibration or movement in any direction. The needle is thus automatically held in 10 place upon the mere act of inserting it in its hole, and upon its withdrawal or removal the tension of the spring rocks the lever to the position shown in Fig. 7 to throw the cam-face of the jaw into the path 15 of the next needle that is inserted.

By forming the lever so that its portions on opposite sides of its pivot are arranged at an obtuse angle each portion has an inward departure away from the sleeve when 20 the other portion abuts against the sleeve, and by this arrangement I provide a needle-holder that automatically secures the needle in its position upon its mere insertion, and without any further effort or attention upon 25 the part of the operator. Also, the spring-pressed lever acts as an absorber that reduces the scratching and metallic sounds frequently produced by phonographs, and in case a scratched or worn record is played 30 by the machine it avoids reproducing the sounds due to such defects; it takes up or absorbs the shocks on the needle caused by defective portions of the record, and reduces the sounds that usually are caused by 35 them.

I claim:

1. A needle-holder for sound-reproducing machines comprising a cylindrical body and tubular sleeve forming a permanent casing,

the body having an axial bore and kerf, 40 a cross-bore at the base of the kerf, and an opposite pair of seats at the sides of the kerf, a spring in the cross-bore, a lever in the kerf having a pintle held in the seats by the sleeve, the opposite portions of 45 the lever being arranged at an obtuse angle forming a jaw to engage the needle and a finger compressing the spring.

2. A needle-holder for sound-reproducing machines comprising a cylindrical body and 50 tubular sleeve forming a permanent casing, the body having an axial bore and kerf, a cross-bore at the base of the kerf, and an opposite pair of seats at the sides of the kerf, a spring in the cross-bore, a lever 55 in the kerf having a pintle held in the seats by the sleeve, the outer end of the lever forming a jaw to engage the needle and its inner end being beveled inwardly and compressing the spring.

3. A needle-holder for sound-reproducing machines comprising a cylindrical body and tubular sleeve forming a permanent casing, the body having an axial bore and 60 kerf, a cross-bore at the base of the kerf, an 65 opposite pair of seats at the sides of the kerf, the bore having a bell-mouth with a V-shaped groove opposite the kerf, a lever in the kerf having a pintle held in the seats by the sleeve, the outer end of the lever 70 forming a jaw to close the V-shaped groove to form a triangular seat for the needle and its inner end being reduced in width and 75 beveled inwardly, and a spring in the cross-bore compressed by the reduced end of the lever.

ERNEST C. KUEHL.
